UNITED STATES PATENT OFFICE.

CORNELIUS S. CLARK, OF NORFOLK, VIRGINIA, ASSIGNOR TO CLARK ENGINEERING CORPORATION, OF NORFOLK, VIRGINIA, A CORPORATION OF VIRGINIA.

VACUUM MEANS FOR CONSERVING LUBRICATING OIL OF INTERNAL-COMBUSTION ENGINES.

Application filed December 11, 1923. Serial No. 680,031.

This invention relates to vacuum means for conserving the lubricating oil of internal combustion engines, and has for its main object an arrangement of structure by means of which the surplus oil passing from the crank case to the combustion chamber between the cylinder and piston, and the non-volatile fuel fraction passing by the same route from the combustion chamber to the crank case, are withdrawn by suction, and delivered to the intake of the engine to form a part of the combustible mixture. By this means, not only is the incrustation of charred oil on the walls of the combustion chamber prevented, but dilution of the crank case oil is avoided, preserving the viscosity and lubricating properties of the oil.

Another object of the invention is the novel piston and cylinder construction which makes possible the withdrawal of the surplus substances in the manner set forth.

For the attainment of these ends and the accomplishment of other new and useful objects, as will appear, the invention consists in the features of novelty in the construction, combination and arrangement of the several parts generally shown in the accompanying drawings and described in the specification, but more particularly pointed out in the appended claim.

In the drawings:—

Figure 1 is a side elevation of a multi-cylinder internal combustion engine, illustrating the invention, two of the cylinders being shown in section.

Figure 2 is an elevation, in section, of a single cylinder showing a modified form of the invention with the piston at the top of its stroke.

Figure 3 is a similar view, parts being broken away, the piston being shown at the bottom of its stroke.

Figure 4 is a cross section taken along the line 4—4 of Figure 3.

Referring now in detail to the several figures, the numeral 1 represents the cylinder block of a multi-cylinder internal combustion engine, the intake manifold of which is represented at 2. For the purpose of carrying out my invention, the walls of each of the cylinders are formed with an annular groove 3 adjacent the lower limit of the range of travel of the piston. Each of these grooves is in communication with a con-

duit 4, said conduits being branches of a common oil manifold 5 which is connected by a pipe 6 into the intake manifold 2. It is quite clear that the suction within the intake manifold induced by the downward movement of the pistons on the intake stroke will be communicated to the annular grooves 3. In each of the modifications shown the pistons must be of such length relative to the stroke thereof, that the grooves 3 are constantly within the range of travel of said pistons. Otherwise, were the top of the pistons to descend below the annular grooves, or were the lower ends of said pistons to rise above said grooves the vacuum in the manifold 2 would be filled by atmosphere from either the combustion chamber or crank case, interrupting the functioning of the carbureter.

In the form of the invention shown in Figure 1, the piston is provided at its top with a single ring groove 7 which may carry a sealing ring 8 of any approved type, but preferably a composite ring, also constituting my invention and claimed and described in a companion application for Patent No. 680,032. The skirt 9 of this piston is without a ring groove at the bottom, so that the sealing effect is mostly at the top, and the vacuum oil conserving system may be expected to draw a considerable proportion of the crank case vapor into the intake manifold along with the surplus oil or liquid fuel that may find its way between the piston and cylinder. The introduction of such vapor into the intake manifold is not objectionable, as it consists largely of more or less volatile combustible gas and adds to the richness of the mixture fed to the engine, to compensate for which a leaner adjustment of the carbureter (not shown) may be made. This form of piston has the advantage that, providing the skirt is long enough to cover the annular groove 3 when the piston is at its upper dead center, any of the ordinary forms of plain skirt piston may be adapted to use with the oil conserving system without material change. It is essential that the piston ring 8 does not pass across the annular groove 3; or it may spread into said groove and lock the piston against further movement. It is preferable, however, that the piston ring 8 should descend slightly below the upper edge of the groove.

3 as shown at 10 in Figure 1 to avoid the wearing of a ridge in the cylinder wall at a point where the piston ring stops. The action of the piston ring is that of scraping the oil down the side of the cylinder into the annular groove 3 whence it is carried into the intake manifold by suction.

In Figures 2 and 3 is shown a modified form of the invention in which the annular groove is omitted from the cylinder wall, the oil-collecting groove being formed upon the piston body below the upper piston ring. This groove may be of any desired form but is preferably shown as a spiral 11 encircling the piston several times so as to cover a zone as wide as approximately one-third of the piston stroke. By this means, the oil-collecting groove 11 comes into registry with the nipple 12 when the piston has travelled two-thirds its distance on the suction stroke, as shown in the dotted line position of the piston in Fig. 2. Prior to this time the nipple is out of registry with the spiral groove, and the vacuum draft from the intake manifold, upon the joint between the cylinder and piston is relatively inactive so that lubrication of the piston is not interfered with. But as the piston descends the vacuum in the combustion chamber increases so that just prior to the opening of the intake valve the pumping of oil past the piston ring and into the combustion chamber becomes acute. It is at this time, just before the opening of the intake valve 15, and continuing to the end of the downward stroke of the piston that the nipple 12 is in communication with the spiral groove 11, the same suction which prevails in the combustion chamber being applied to the spiral groove through the nipple 12, counter-acting the pumping action of the combustion chamber and withdrawing the surplus oil from the spiral groove into the intake manifold 2. For the purpose of ensuring proper lubrication of the reciprocating parts it is advisable to segregate the piston ring groove 7 from the spiral groove 11, to which end I have provided that the spiral groove shall terminate in a circular portion 13 just below the piston ring groove 7 but out of communication therewith.

In the form of the invention shown in Figures 2 and 3 the pistons are each provided with a piston ring 14 at the lower

end of the skirt, more effectively sealing the space between the piston and cylinder walls, and avoiding, to a great extent the induction of crank case vapors into the intake manifold. In some designs of internal combustion engine this may be found preferable to the form of invention illustrated in Figure 1. Where a piston ring is used adjacent the inner end of the piston skirt, it is essential that the length of the lower end of the cylinder be made sufficient to prevent the spreading of the ring into the crank case chamber below the end of the cylinder.

It will be understood that wherever the term oil is used throughout the specification and claim it is intended to cover not only the surplus lubricating oil which may be pumped up from the crank case between the cylinder piston walls but also the less volatile portion of the fuel mixture which may condense within the combustion chamber during the compression and explosion strokes of the engine, and which if permitted to mix with the crank case oil would soon destroy the lubricating properties of the same.

I consider that my invention, resides primarily in the broad aspects hereinbefore set forth, and only secondarily in the details of construction and arrangement, wherefore I do not restrict myself to the particular construction here disclosed, but only by the terms of the claim and the state of the prior art.

Having described my invention what I claim as new and desire to secure by Letters Patent, is:—

In an internal combustion engine, a cylinder, a piston reciprocable therein, the wall of said cylinder being provided with a port adjacent the lower limit of the range of travel of said piston, means establishing communication between said port and the combustible mixture intake of said engine, a piston ring adjacent the upper end of said piston and an oil collecting groove arranged around said piston below said piston ring and covering a zone of such width as to bring the lower portion of said oil collecting groove into registry with said port substantially at the time of opening of the inlet valve engine.

In testimony whereof I have hereunto set my hand.

CORNELIUS S. CLARK.
